[57] CLAIM

The ornamental design for a combined reel feeder mounting rack and detachable feeder for use in printed circuit assembly machines, substantially as shown and described.

DESCRIPTION

FIG. 1 is a front perspective view of a combined reel feeder mounting rack and detachable feeder for use in printed circuit assembly machines showing my new design;

FIG. 2 is an enlarged left side elevational view thereof;

FIG. 3 is an enlarged top plan view thereof;

FIG. 4 is an enlarged bottom plan view thereof;

FIG. 5 is an enlarged front elevational view thereof;

FIG. 6 is an enlarged rear elevational view thereof.
